RADIANT HEATING APPARATUS

John Kaminski, Altadena, Calif.

Application April 14, 1942, Serial No. 438,880

12 Claims. (Cl. 219—34)

This invention relates to apparatus for heating objects by radiant energy, and is particularly useful for drying paint on automobiles and the like.

It is old to dry paint on automobiles with heat derived from infrared lamps, but prior methods have required the use of very large numbers of lamps, sufficient to at least blanket the entire surface being heated. This is objectionable, not only because it requires a large investment in lamps, but because it involves an electric power drain so heavy that it cannot be supplied over the wiring of the average paint shop. In some instances, automobiles have been moved slowly through a tunnel lined with infrared lamps, but such a system requires so many lamps that it is quite impractical except in very large establishments, such as automobile manufacturing plants.

Another defect of prior systems known to me, particularly the tunnel system, is that the heat is unequally applied to different portions of the painted surfaces, and excessive heat is applied to the windows of the automobile unless they are specially protected. Thus it is quite apparent that an automobile passing through a drying tunnel would have its sides and top, including the side windows, exposed to full intensity of heat, whereas the front and rear end surfaces would be inadequately heated.

An object of the present invention is to provide a practicable apparatus for drying paint on automobiles by radiant energy without the use of an excessive number of lamps and without excessive power drain.

Another object is to heat all portions of the painted surface approximately equally.

Another object is to reduce, or substantially eliminate, the application of heat to window areas of the automobile.

Another object is to provide an infrared heating apparatus for drying paint on automobiles, so constructed that it can be installed in the paintroom where the paint is sprayed onto the automobile, so that the latter need not be disturbed, after being sprayed, until the paint has been dried.

Another object is to provide a radiant heating system for drying paint on automobiles that can be adjusted to bring the heating lamps into relatively close spacing with practically all portions of the automobile surface so as to increase the efficiency and produce equal baking of all portions of the automobile surface.

My apparatus, whereby I attain the foregoing

objects, differs essentially from prior-known apparatus in that instead of employing sufficient heating lamps to simultaneously blanket the entire painted surface of the automobile, it employs one or more rows of heat lamps of relatively high intensity positioned close to the surface of the automobile, with a mechanism for slowly moving the row of lamps along and approximately parallel to the automobile surface, so as to successively heat different portions thereof.

Because of the irregular shape of an automobile, special supporting mechanisms are employed to move the lamps in the particular manner described, and the invention will now be explained by describing in detail one form of the invention as illustrated in the drawings, in which

Fig. 1 is a plan view, partly in section, showing 20 a spraying and drying room equipped with paint-drying equipment in accordance with the invention;

Fig. 2 is a side elevation, showing one-half of 25 the apparatus, the view being taken along the line II—II of Fig. 1;

Fig. 3 is a schematic diagram illustrating the 30 mechanical movements for moving the heat lamps along an automobile, while maintaining them in close proximity thereto;

Fig. 4 is a detail side elevation of one of the 35 front lamp-supporting units of my apparatus;

Fig. 5 is a plan view of the apparatus shown in elevation in Fig. 4;

Fig. 6 is a detail vertical section, taken in 35 the plane VI—VI of Fig. 5;

Fig. 7 is a detail plan view of a driving unit 40 for the apparatus;

Fig. 8 is a detail plan view of one of the rear 45 lamp-supporting units;

Fig. 9 is a detail vertical section in the plane IX—IX of Fig. 8;

Fig. 10 is a detail vertical section in the plane X—X of Fig. 8;

Fig. 11 is a detail vertical section in the plane 45 XI—XI of Fig. 8;

Fig. 12 is a detail elevation showing a tripping mechanism associated with the rear lamp carriers; and

Fig. 13 is a view taken at right angles to that 50 of Fig. 12, showing the apparatus at the time of tripping.

Referring to Fig. 1, there is shown, in plan, a room dimensioned to contain an automobile with sufficient clearance to permit use of a spray gun on all sides of the automobile for painting it. As

shown, this room has a right wall 20, a front wall 21, a left wall 22, and doors 23 for closing the rear end of the room. The heating equipment in accordance with the present invention, for drying the paint on an automobile after it has been applied thereto, is mounted on the walls 20, 21 and 22 of the room. As will appear later, all portions of the apparatus can be folded up quite close to the walls of the room so as to be out of the way during the painting operation. Thereafter the apparatus is quickly adjustable to heat the automobile and dry the paint thereon.

Heat lamps 24 are employed as the source of heat, and they are divided into four groups, each group consisting of a row of lamps supported on one of four lamp arms 25, 26, 27 and 28, respectively. The arms 25 and 26 are mounted on opposite walls of the room and together constitute a yoke bracketing the rear portion of the automobile. Similarly the front lamp arms 27 and 28 are mounted on opposite walls of the room and together form a yoke bracketing the front portion of the automobile. The separate arms 25, 26, 27 and 28 are employed, instead of using two continuous yoke-shaped arms, to facilitate folding the arms out of the way when not in use. However, the mechanism is such that the arms 25 and 26 move in unison with each other, and the arms 27 and 28 move in unison with each other, during the heating operation.

Fig. 1 shows the positions of the lamp arms 25 to 28, inclusive, at the beginning of a heating or drying operation. It will be observed that at this time the arms 25 and 26 lie in substantially a horizontal plane at the lower edge of the automobile body and the arms 27 and 28 lie in a vertical plane just above the rear portion of the hood of the automobile, the lower ends of the arms being substantially level with the lower edge of the automobile body, as shown in Fig. 2. The supporting mechanism for the lamp arms is such that, when the apparatus is started, the rear arms 25 and 26 are swung slowly up over the rear end of the automobile until the arms are in a vertical plane, after which they advance forwardly almost to the position initially occupied by the front lamp arms 27 and 28. At the same time, the front arms move slowly forwardly above the hood and front fenders of the automobile until they are near the forward end thereof, after which they swing forwardly and downwardly to heat the front ends of the hood and the front fenders. At the end of the operation, the rear arms 25 and 26 are close to the initial position of the front arms 27 and 28 (as shown in Figs. 1 and 2), and the front arms occupy a substantially horizontal position along the front lower margin of the automobile body, corresponding to the initial position of the rear arms 25 and 26. Means is provided for automatically stopping the movements of the lamp arms and cutting off the power supplied to the lamps at the completion of the operation, so that after starting the mechanism the operator can go away and forget about it. Such automatic control is desirable not only from the labor-saving standpoint but because the room can be left closed, thereby reducing the opportunity for dust to collect on the tacky painted surface.

As already indicated, the lamp arms 25 and 27 are completely supported by apparatus mounted on the right wall 20, and the arms 26 and 28 are completely supported on the left wall 22. The apparatus on one wall is the mirror image of the apparatus on the other wall. Therefore it

will be sufficient to describe in detail the apparatus for supporting and moving the two lamp arms 25 and 27.

The arm 25 has rigidly secured thereto at spaced apart points thereon a pair of legs 30 and 31, respectively, which are interconnected at their opposite ends by a shaft 32 (Fig. 10), which extends through and is supported by a sleeve 33. The sleeve 33 in turn is connected at its opposite ends to the outer ends of a pair of arms 34 and 35, which are rigidly secured at their inner ends to a pivotal plate 36 (Fig. 2) secured by a pivotal bolt 37 to the face of a carriage 38 which is slideable on a horizontal track 39 extending alongside the wall 20.

During a painting operation, the shaft 32, which carries the arm 25 is prevented from rotating within the sleeve 33 by a locking pin 95 inserted through suitable registering apertures in the shaft 32 and the sleeve 33. However, when the device is not in use, the pin 95 is removed and the arm 25 with its lamps is swung into position alongside the wall 20 so as to be out of the way while the automobile is being moved into or out of the room and while it is being painted.

The track 39 may consist of two tubular members 40 supported at intervals by hangers 41 secured directly to the wall 20. One of these hangers 41 is shown in Fig. 9. It will be observed that the hanger is secured, as by welding, to the underside of the upper tubular member and to the upper side of the lower tubular member, and that the carriage 38 has flanges or lips 42 extending over the upper side of the upper tubular member and under the lower side of the lower tubular member, so that the movement of the carriage is not interfered with by the track-supporting brackets 41.

The carriages are moved forwardly along the track 39 by a reciprocating bar 43 through a suitable clutch mechanism, to be described later. The reciprocating bar 43 rests loosely upon the brackets 41. The two bars 43 on the two opposite sides of the room are reciprocated in unison with each other by a common drive mechanism.

Referring to Figs. 1 and 7, the source of driving power is an electric motor 44 mounted in one front corner of the room, which motor has a shaft connected to a worm 45 meshing with a wormwheel 46 keyed to a shaft 47, which is supported for rotation in a bearing 48 secured to the front wall 21, a bearing 49 secured to the forward end of the track 39, and a bearing 50 secured to a bracket 51. Intermediate the bearings 49 and 50, the shaft 47 has an eccentric journal 52, which is coupled by a connecting rod 53 and a clevis 54 to the forward end of the reciprocating bar 43. It will be observed that rotation of the shaft of the electric motor 44 rotates the shaft 47 at reduced speed, which in turn continually reciprocates the bar 43 through a short stroke.

Still referring to Fig. 7, the lower end of the shaft 47 is connected to a shaft 55 which extends along the front wall 21 (Fig. 1) and connects to a shaft corresponding to shaft 47, which drives a rod mounted on the left wall 22, corresponding to the rod 43, so that the apparatus on both walls 20 and 22 is driven in unison.

Referring to Figs. 8 and 11, a clutch is disclosed for advancing the carriage 38 forwardly in response to each forward reciprocation of the bar 75 43 and releasing the carriage from the bar dur-

ing rearward reciprocation of the latter. Thus a box frame 56 is secured to the rear wall of the carriage 38 and has end walls 57 and 58 containing guide apertures through which the bar 43 extends. Positioned within the box frame 56 is a wedging plate 59 having an aperture 60 through which the bar 43 extends. The aperture 60 is slightly larger than the bar 43, so that when the plate is perpendicular to the bar (as shown in dotted lines in Fig. 11), the latter can slide freely through the plate. However, if the plate is canted slightly (the position shown in full lines in Fig. 11), it grips the bar 43 tightly and will be moved therewith. The lower end of the wedge plate 59 extends between a pair of transverse pins 61 secured to the box frame 56, to provide a pivotal support for the wedge plate at its lower end. Furthermore, the plate is constantly urged into binding position by a helical spring 62 which surrounds the rod 43 and is compressed between the wedge plate 59 and the end wall 58 of the box member.

It will be obvious from an inspection of Fig. 11 that when the bar 43 is moving forwardly through its stroke (to the left in Fig. 11) the wedge plate 59 is locked to the bar so that the bar carries the wedge plate, the box member 56 and the carriage 38 forwardly with it. However, during the return stroke of the bar 43 (to the right in Fig. 11), initial movement of the bar rocks the wedge plate 59 into the dotted line position against the force exerted by the spring 62, thereby releasing the wedge plate from locking engagement with the bar and permitting the latter to slide through the wedge plate during the remainder of its stroke. However, as soon as the bar 43 resumes its forward motion it again locks with the wedge plate 59 and carries the carriage along with it.

It will be observed from Fig. 2 that the rear lamp arm 25 is initially in substantially horizontal position, and the arm must be swung upwardly and forwardly into a vertical plane before it is advanced bodily along the automobile. To produce such a movement, I employ a link 63 for restraining forward movement of the lower end of the arm 25 until the latter has been swung into substantially vertical position. This link 63 is pivotally connected at its rear end to a pin 64 on an upward extension 65 on the rear end of the track 39, and at its forward end it is pivotally connected to an extension 66 (Fig. 10) of the shaft 32. Thus a pin 67, extending from the side of the extension 66, is engaged in a notch 68 (Fig. 13) in the underside of the forward end of the link 63.

Progressive movement of the arm 25, from the starting position shown in Fig. 2 into vertical position, is shown in the diagram of Fig. 3. When the arm has reached the vertical position indicated at C in Fig. 3, the link 63 is automatically disconnected from the extension 66 so that it will thereafter permit bodily forward movement of the arm 25 without further rotation of the arm with respect to the carriage 38. This automatic disconnection is effected by providing an adjustable lip 69 (Figs. 12 and 13) on the extension 66 which, by the time the extension has swung into vertical position, has swung the link 63 to carry the notch 68 clear of the pin 67, as shown in Fig. 13. The lip 69 is so inclined that the notch 68 will not engage it. As the extension 66 moves away from the link 63 the lower end of the latter simply drops to the floor, where it remains until

the apparatus is reset for painting another automobile.

It is desirable to provide an automatic holding structure for retaining the lamp arm 25 in its vertical position following disconnection of the link 63. To this end, I provide a holding link 70 (Fig. 2) which is pivotally connected at its lower end to the arm 35 and extends through a clutch mechanism 71 similar to the clutch mechanism described with reference to Fig. 11, and pivotally mounted on a vertical extension 72 (Fig. 9) on the rear end of the carriage 38. The clutch 71, as illustrated in Figs. 9 and 10 is so arranged as to permit upward movement of the bar 70 therethrough, but prevent downward movement.

After the arm 25 has been swung into the vertical position indicated at C in Fig. 3, it moves forward bodily with the carriage 38 until the lamp arm nearly reaches the position initially occupied by the front lamp arm 27 (Fig. 1). At that time the arm is automatically stopped by release of the wedge bar 59. To this end, there is mounted on the wall 20 above the track 39 a flat bar 73, on which is mounted an adjustable stop 74, which can be slid along the bar 73 and locked in any position thereon by tightening a set screw 75. The stop 74 has a horizontal arm 76 projecting laterally therefrom, and the bar 73 is mounted at such a height that the horizontal arm 76 is on the level with the lever 77 of a standard toggle switch 78 mounted on the carriage 38. The switch 78 is connected in the circuit of all of the lamps on the arm 25, and the switch is "on" when the lever 77 is to the left (with reference to Fig. 8) and is "off" when the lever is swung to the right. The stop 74 is so adjusted on the bar 73 that when the front arm has traveled as far forwardly as is desired for the particular automobile to be baked, the arm 76 intercepts the switch lever 77 and snaps it over, thereby shutting off all the lamps on the arm. At the same time that the arm 76 intercepts the switch lever 77 it intercepts an upstanding arm 79 positioned alongside the switch lever 77 and secured to a slide plate 80 slidably supported on the top plate of the switch 78 by headed pins 81 which extend through slots 82 in the slide plate, thereby moving the slide plate to the right simultaneously with the switch lever 77. The slide plate 80 is joined to a rod 83 which extends forwardly therefrom and through a hole 84 (Fig. 11) provided therefor in the upper end of the wedge plate 59. The forward end of the rod 83 is threaded to receive stop nuts 84. These stop nuts are so adjusted that the movement of the plate 80 by the arm 76 carries the stop nut 84 against the wedge plate 59, to swing it into the release position shown in dotted lines, to thereby prevent further forward movement of the lamp arm.

Summarizing the operation of the rear lamp arm 25: The arm is first manually set in the lowermost and rearmost position shown in Figs. 1 and 2, the motor 44 is started, and the switch lever 77 is moved forward manually to light the lamps on the arm. Thereafter, in response to the slow continual reciprocation of the bar 43 by the motor 44, the carriage 38 is successively moved forwardly by small increments by the automatic action of the clutch shown in Fig. 11. This forward movement of the carriage initially causes the arm 25 to swing up over the rear end of the automobile, by virtue of the fact that the link 63 restrains the lower end of the arm against

advancing movement. However, when the arm attains substantially vertical position, the link 63 is tripped off the pin 67 (Fig. 12) by action of the lip 69, the arm being prevented from falling back down into horizontal position by the holding clutch 71 acting on the rod 70. Thereafter the lamp arm is advanced bodily along the automobile until it is nearly opposite the windshield of the automobile, whereupon its movement is stopped and its lights are extinguished by action of the stop plate 74 on the switch lever 77, and the upstanding arm 79, as described.

It is sometimes desirable to shut off those lamps that are juxtaposed to the side windows of the automobile as the arm traverses the windows, to avoid applying excessive heat to the glass. I therefore make provision for shutting off two of the lamps 24a after the arm 25 has completed its swinging movement over the curved rear end of the automobile and is about to commence its linear forward movement. To effect this operation, these particular lamps 24a are energized through an additional conventional toggle switch 85 (Fig. 10) mounted on the sleeve 33 and upper arm 35 which supports the lamp arm. This toggle switch 85 is so positioned that its lever 86 comes into contact with an adjustable stop 87 (Fig. 9) just before the lamp arm completes its upward movement, so that final upward movement trips the lever 86 of the switch into lower position to shut off the two lamps 24a. The adjustable stop 87 is mounted on the housing of the clutch 71 which itself is mounted on the extension 72 of the carriage 38.

To facilitate manual movement of the carriage 38 along the track 39 when initially setting the apparatus, a special release is provided for the wedge plate 59 (Fig. 11). This release comprises a rod 89 extending through an aperture provided therefor in the forward wall 57 of the box frame 56, and having an inner headed end 90 which is constantly urged toward the wedge plate 59 in direction to release the latter, by a helical spring 91 surrounding the rod 89 and compressed between the head 90 thereon and the end plate 57. The rod 89 extends some distance forwardly beyond the wall 57 and has its forward end bent laterally outwardly, as indicated at 92 (Figs. 8 and 11) to form a lateral arm 92. The projecting portion of rod 89 is partially surrounded by a semicylindrical stop 93, and when the lateral arm 92 extends horizontally, as shown in Figs. 8 and 11, it rests against the end of this semicylindrical stop 93 and maintains the spring 91 compressed. However, by rotating the lateral arm 92 upwardly it can be disengaged from the stop 93, whereupon the spring 91 is effective to move the head 90 against the wedge plate 59 and carry the latter into the released position shown in dotted lines in Fig. 11.

There has been shown in Figs. 1 and 2 an automobile body of the coupe type, in which the passenger portion of the body is relatively short and slopes rather gradually back to the tail. With a body of this type, the link 63 should be relatively long, as shown, in order to produce a relatively slow rise of the lamp arm 25, so that the latter will not reach full vertical position until it has, by its forward movement, reached the highest part of the body. However, when an automobile of a different type, such as a sedan, having a more abruptly sloping rear end, is being dried, the lamp arm 25 should rise more rapidly, relative to the advancement of the carriage 38 along the track 39. Such movement

can be readily effected by shortening the effective length of the link 63, and the link can be given any desired effective length less than its full length by providing auxiliary holes 63a for engagement with the pin 64. Of course when (referring to Fig. 2) the hole 63a is engaged with the pin 64, the carriage 38 must be moved further rearward than as shown in Fig. 2, in order to obtain the desired low starting position of the lamp arm 25. This is natural, since there is a larger area of surface to heat on a sedan than on a coupe, and, since the speed of movement of the carriage is fixed, it must travel a greater distance to secure the same radiation on a longer body. Only one hole 63a is shown in the rod 63, since it is found by experience that with most modern automobiles one positioning of the hole 63a will take care of all modern sedans, just as one hole at the extreme rear end of the link will take care of modern coupes. However, it will be obvious that more accurate adjustment of the motion of the device can be obtained, if desired, by providing a larger number of holes in the link 63.

As previously stated, the front arm 27 is adapted to move forwardly over the hood and front fenders and then downwardly over the front end of the hood and fenders. The construction for producing this movement will now be described. The lamp arm 27 is connected by arms 100 and 101 (Figs. 1 and 4) to a shaft 102 which shaft is rotatably supported by a sleeve 103, corresponding to the sleeve 33 which supports the rear lamp arm 25. The shaft 102 is adapted to be locked against rotation with respect to the sleeve 103 by a pin 104 when the device is in use. When it is not in use, the pin is removed to permit the lamp arm to be swung flat against the wall 20, out of the way.

The sleeve 103 is secured by a pair of arms 105 to a pivotal plate 106 pivotally held by a bolt 107 against a carriage 108 which rides on the track 39 in the same manner that the rear carriage 38 rides thereon. This carriage 108 is connected by a clutch 109, corresponding to the clutch of Fig. 11, to the reciprocating bar 43 for forward movement by the latter.

As shown in Figs. 1 and 2, the lamp arm 27 is initially positioned opposite the rear end of the hood, and during the major portion of its forward movement the lamp arm is held in vertical position by a roller 110 (Fig. 4) on the arm 105, which roller rides on an auxiliary track 111 positioned immediately below the lower tubular member of the track 39. The track 111 extends horizontally for a distance and then bends sharply into a vertical downwardly extending section 112. As the forward movement of the carriage 108 progresses, the roller 110 rides around the bend 113 onto the vertical track 112, which permits the pivot plate 106 and the arm 105 and the lamp arm 27 to swing about the pivot point 107 in response to further forward movement of the carriage 108. As a result, by the time the carriage 108 has reached the forward limit of its motion, the arms 105 extend almost vertically down, and the lamp arm 27 has been moved into a nearly horizontal plane adjacent the lower side and front edges of the hood and fender of the automobile. In fact the finished position of the front lamp arm 27 corresponds closely to the starting position of the rear lamp arm 25 as the latter is shown in Figs. 1 and 2. However, whereas the link 63 (Fig. 2) causes the rear lamp arm 25 to rise gradually and thereby follow the grad-

ually sloping rear portion of the automobile, the roller 110 and tracks 111 and 112 cause the front lamp arm 27 to swing downward much more sharply so as to maintain the lamps in relatively uniform spaced relation with the approximately vertical surfaces at the front and sides of the automobile hood and fenders.

To help support the weight of the front arm assembly, as the roller 110 rides down along the vertical track 112, I provide a yieldable support consisting of a pair of arms 115 and 116 and a torsion spring 117. The arm 115 is pivotally connected at one end by a pivot 118 to the track 112 near the lower end thereof, and is pivotally connected at its other end by a pivot 119 to one end of the arm 116. The other end of the arm 116 is pivotally connected by a pin 120 to a carriage 121 slidable on the track 112 and having a shelf 122 which is engaged by the roller 110 as the latter moves over the bend 113. The inner end of the torsion spring 117 is connected to the arm 115 and the outer end is connected to the arm 116 so as to tend to maintain the latter in the upper position shown in Fig. 4. The force of the spring 117 is insufficient to completely support the weight of the lamp arm, so it does not prevent the downward movement of the roller 110 as the carriage 108 moves forwardly. However, it does prevent the weight of the lamp arm from moving the carriage 108 forwardly along the track 39 faster than it is normally advanced by the reciprocatory bar 43.

Slightly before the lamp arm 27 reaches its final position adjacent the bottom edges of the hood and fenders of the automobile, the carriage 108 is stopped by release of its associated clutch 109. This clutch, which corresponds in structure to the clutch shown in Fig. 11, has a release pin 89 terminating in a transverse arm 92, and as the carriage 108 approaches its final position the arm 92 reaches and rides up on an inclined trip 123 secured to the track 39 by a clamp 124 (Fig. 4). The inclined surface 123 rotates the arm 92 out of engagement with its stop wall 93, permitting the spring 91 to move the head 90 of the pin 89 against the wedge plate 59 of the clutch and release it from the reciprocatory bar 43.

The stop mechanism is also employed to shut off the current to the lamps on the arm 27. Thus there is provided on the clamp 124 (Fig. 5) an adjustable stop 127 adapted to contact the forward end of a rod 128 which is slidably mounted on the carriage 108 by guides 129 and has its rear end extending transversely to form an arm 130 normally positioned in front of the lever 131 of a standard toggle switch 132 in the lamp circuit. Slightly before the pin 89 is tripped, the forward end of the rod 128 contacts the stop 127, and the final forward movement of the carriage 108 shifts the arm 130 rearwardly a sufficient distance to actuate the toggle switch lever 131. Electrical connections between the lamps, switches and any suitable power supply line can be completed by flexible cords, some of which are shown in Fig. 1, but the remainder have been omitted to simplify the drawings.

The track 111, with its integral vertical track 112, is longitudinally adjustably supported so that it can be properly positioned for different size automobiles. To this end, the forward end of the track 111 is supported by a bracket 135 secured to and extending rearwardly from the clamp 124, and the rear end of the track 111 is slidably supported on a bracket 136 (Fig. 5) ex-

tending from one of the brackets 41. The lower end of the track 112 is slidably supported against lateral swinging movement by a track 137 which is secured at its opposite ends to the wall 20.

5 The track 137 extends through a hole provided therefor in the lower end of the tubular track 112, and the latter can be locked to the track 137 by a handscrew 138.

Although for the purpose of explaining the invention a particular embodiment thereof has been described in detail, it is to be understood that various changes can be made in the constructions shown without departing from the invention, which is to be limited only to the extent set forth in the appended claims.

I claim:

1. Apparatus for applying radiant energy to the surface of an object such as an automobile, said apparatus comprising: an energy-radiating device having a first elongated section approximately parallel to one side of said object and a second integral section extending from one end of said first section at approximately a right angle thereto, said second section extending across said object, carriage means for supporting said device, means for moving said carriage means alongside said object substantially parallel to said one side, and means for swinging said device with respect to said carriage means from a first position in which both said sections lie substantially in a common horizontal plane, into a second position in which both said sections lie in a common vertical plane, with said second section extending substantially transversely of said object.

2. Apparatus for applying radiant energy to the surface of an object such as an automobile, said apparatus comprising: a device for emanating radiant energy and having a first elongated section approximately parallel to one side of said object, and a second integral section extending from one end of said first section at a right angle thereto across said object, carriage means for supporting said device, means for moving said carriage means alongside said object substantially parallel to said one side, and means for swinging said device relative to said carriage means from a first position in which said first section is vertical and said second section extends horizontally above said object into a second position in which both said sections are substantially horizontal and juxtaposed to side and end portions respectively of said object.

3. Apparatus for applying radiant energy to the surface of an object such as an automobile, said apparatus comprising: a device for emanating radiant energy extending approximately transversely across said object, a track extending alongside of and parallel to said object, carriage means on said track, means for moving said carriage along said track, means pivotally mounted on said carriage for supporting said device for movement in a curved path over an end portion of said object, and means for swinging said device on its carriage simultaneously with movement of said carriage along said track.

4. Apparatus for applying radiant energy to the surface of an object such as an automobile, said apparatus comprising: a device for emanating radiant energy extending approximately transversely across said object, a track extending alongside of and parallel to said object, carriage means on said track, means for moving said carriage along said track, means pivotally mounted on said carriage for supporting said device for

movement in a curved path over an end portion of said object, and means for swinging said device on its carriage in response to movement of said carriage along said track.

5. Apparatus for applying radiant energy to the surface of an object such as an automobile, said apparatus comprising: a horizontal track alongside which said object is adapted to be positioned, a device for radiating energy extending across said object, a carriage on said track, means pivotally supporting said device on said carriage for swinging movement with respect to the carriage, stationary anchor means, nonextensible link means connecting said anchor means to a portion of said radiating means vertically displaced from the pivot point on said carriage, means for advancing said carriage along said track, whereby relative movement of the carriage with respect to said anchor member produces a force couple for swinging said device about said pivot point, and means for advancing said carriage, to swing said device from a position extending across one end of said object to a higher position extending across the top of the object.

6. Apparatus as described in claim 5 with means for releasing said link in response to full elevation of said radiating means whereby the further movement of said carriage along said track imparts linear movement only to said device.

7. Apparatus as described in claim 5, including oneway clutch means for preventing reverse swinging movement of said device on said carriage, and means for disengaging said link means and thereby stopping the swinging movement of said device following a predetermined swinging movement.

8. In apparatus for applying radiant energy to the surface of an object such as an automobile, having side windows extending thereabove at a predetermined level, said automobile sloping downwardly and rearwardly back of the last window: a device for emanating radiant energy comprising an elongated frame positioned in a plane parallel to said one side of said automobile and having a plurality of radiating devices in a longitudinal row thereon, means for moving said device from an initial, horizontal position substantially juxtaposed to the rear, lower side margin of the automobile into a vertical position substantially juxtaposed to the rear edge of said windows of said automobile, and thence bodily horizontally along the side of said automobile, predetermined ones of said radiating devices being juxtaposed to said windows during the last-mentioned linear movement of said device, and switch means operable in response to movement of said device for deenergizing only said predetermined radiating devices in response to movement of the device into position juxtaposed to said windows.

9. Apparatus for applying radiant energy to the surface of an automobile having a passenger compartment merging at its forward end into a hood with a windshield positioned at the juncture of said passenger compartment and hood, said apparatus comprising: a first radiating de-

vice initially extending across the rear end of said automobile, a second radiating device initially disposed across said automobile immediately in front of said windshield, means for simultaneously advancing both said devices forwardly along said automobile to heat the surface of the latter, first means for stopping said first device before it reaches said windshield, and second means for stopping said second device when it reaches the forward end of said automobile.

10. Apparatus for applying radiant energy to the surface of an object such as an automobile, said apparatus comprising: a device adapted to extend across said object and radiate energy thereon, a horizontal track extending alongside said object, a carriage on said track for movement therealong, arm means supporting said radiating device for swinging movement on said carriage, auxiliary track means having a first section extending parallel to said first track, and a second section extending downwardly from the forward end of said first section, and guide means on said swinging structure adapted to ride on said second track means for controlling swinging movement of said device on said carriage, said means maintaining said device against swinging movement while riding on said first section of said auxiliary track, and permitting rotary swinging movement of said device in response to forward movement of said carriage as said means rides along said second section of said auxiliary track.

11. Apparatus for applying radiant energy to the surface of an object such as an automobile, said apparatus comprising: a horizontal track alongside which said object is adapted to be positioned, a carriage mounted on said track for movement therealong, means for advancing said carriage along said track, a device for emanating radiant energy adapted to extend across said object substantially at right angles to said track, means pivotally supporting said device on said carriage for swinging movement about an axis lying in a vertical plane parallel to said track, whereby said device can be folded away from said object, and means for locking said pivotal mounting means to retain said device in transverse position extending across said object.

12. Apparatus for applying radiant energy to the surface of an object such as an automobile, said apparatus comprising: a device for emanating radiant energy, a track alongside which said object is adapted to be positioned, a carriage mounted on said track for movement therealong, means supporting said device from said carriage for traversing movement of said object in response to movement of said carriage, and means for effecting movement of said carriage along said track comprising a bar extending adjacent and parallel to said track, clutch means on said carriage engaging said bar for preventing relative movement of said bar with respect to said carriage in one direction while permitting it in the other direction, and means for reciprocating said bar.

JOHN KAMINSKI.
